SOLVENT REFINING OF HYDROCARBON OIL

Louis A. Clarke, Fishkill, N. Y., assignor to The Texas Company, New York, N. Y., a corporation of Delaware

No Drawing. Application June 5, 1937,
Serial No. 146,587

2 Claims. (Cl. 196—13)

This invention relates to refining hydrocarbon oil, and more particularly to refining mineral oil by solvent extraction.

The invention contemplates the solvent extraction of hydrocarbon oil with a selective solvent comprising resorcinol monoacetate to separate the oil into fractions having different characteristics.

I have discovered that resorcinol monoacetate is particularly suitable as a solvent refining agent for mineral oil, and especially for the refining of lubricating oil fractions derived from petroleum.

I have also discovered that this solvent, when used for treating mineral lubricating oil, permits obtaining a high yield of high viscosity index oil having a good color as well as other desirable characteristics. In this respect, it is superior to many of the known selective solvents; that is, it is possible to obtain high viscosity index oil of good color without substantially sacrificing the yield.

Treatment of the oil with the solvent may be effected by stage or continuous countercurrent contact. In either case, the mixture of oil and solvent is separated into extract and raffinate phases. The extract phase comprises the so-called naphthenic or low viscosity index constituents of the oil dissolved in the main body of the solvent, while the raffinate phase comprises the so-called paraffinic or high viscosity index constituents of the oil mixed with a small portion of the solvent.

The two phases are separated, and the solvent removed therefrom by distillation or by some other means, for example, washing or displacing the solvent from the oil by contact with some other liquid or solvent.

As a specific example, a lubricating oil distillate obtained from Mid-Continent crude, and having the tests indicated below was extracted with resorcinol monoacetate, using three parts of solvent to one part of distillate, and at a temperature of about 237° F. The mixture was separated into extract and raffinate phases, and the raffinate phase, upon removal of the solvent liquid, comprised about 88% by volume of the original distillate.

The tests on the distillate before extraction, and on the resulting raffinate oil, were as follows:

	Distillate	Raffinate
Gravity, A. P. I.	21.7	24.9
Color Tag, Rob.	Too dark.	1½
S. U. viscosity at 100° F.	1774	1250
S. U. viscosity at 210° F.	99	87.7
Viscosity index	57	70
Viscosity gravity constant	.855	.881

tively high yield of raffinate was obtained, namely, 88%, having a viscosity index of 70, as compared with a viscosity index of 57 for the original distillate.

Oil of still higher viscosity index, of course, can be obtained by altering the solvent proportions and the extraction temperature, in which case a somewhat lower yield of raffinate, corresponding to the higher viscosity index, would be obtained.

It is, therefore, contemplated that extraction temperatures, either below or above that specified above, may be used. Likewise, the solvent dosage may be varied as, for example, from one to four parts of solvent to one of oil. These factors can be varied, depending upon the nature of the oil undergoing treatment as well as upon the degree of extraction desired.

While a distillate oil has been referred to above in the specific example, it is, of course, contemplated that residual fractions may also be treated with the solvent. The solvent is also useful in the extractive treatment of other petroleum fractions, as, for example, naphtha, kerosene, etc.

When treating lubricating oil stock, the oil may be diluted with a suitable diluent such as a low-boiling petroleum hydrocarbon, and the dilute mixture subjected to extraction with the solvent.

Obviously, many modifications and variations of the invention, as hereinbefore set forth, may be made without departing from the spirit and scope thereof, and therefore only such limitations should be imposed as are indicated in the appended claims.

I claim:

1. In the refining of hydrocarbon oil containing relatively paraffinic and relatively non-paraffinic constituents to separate the oil into fractions respectively rich in paraffinic and non-paraffinic constituents, the method which comprises mixing the oil with a selective solvent comprising resorcinol monoacetate, forming an extract phase containing non-paraffinic constituents dissolved in the solvent and a raffinate phase comprising paraffinic constituents of the oil, and separating the two phases.

2. The method of treating mineral lubricating oil containing relatively paraffinic and relatively non-paraffinic constituents to separate the oil into fractions respectively rich in paraffinic and non-paraffinic constituents comprising mixing the oil with a selective solvent comprising resorcinol monoacetate, forming an extract phase containing non-paraffinic constituents dissolved in the solvent and a raffinate phase comprising paraffinic constituents of the oil, and separating the two phases.

From the foregoing, it is observed that a rela-
